UNITED STATES PATENT OFFICE.

JEREMIAH H. MATTHEWS, OF SOUTH BEND, INDIANA.

DOOR-SECURER.

SPECIFICATION forming part of Letters Patent No. 485,205, dated November 1, 1892.

Application filed April 26, 1892. Serial No. 430,796. (No model.)

To all whom it may concern:

Be it known that I, JEREMIAH H. MATTHEWS, a citizen of the United States, residing at South Bend, county of St. Joseph, State of Indiana, 5 have invented a certain new and useful Improvement in Door-Securers, of which the following is a specification, reference being had to the accompanying drawings.

My invention relates to a door-securer which 10 can be carried in the pocket on a key-ring and is always ready and handy to secure a door without the use of a key.

My invention consists of a bolt which has 15 two flat or parallel sides part of its length. On one end there are two spurs at right angles to each other, and at right angles to the bolt proper on the other end is cut a thread, on which is screwed a nut.

In the accompanying drawings, Figure 1 is 20 a perspective view showing both spurs, thread, and hole in end of bolt for insertion on key-ring. Fig. 2 shows a transverse section of a door and frame and how my door-securer is to be inserted between edge of door and jamb. 25 Fig. 3 shows a transverse section of a door and jamb with door closed and my door-securer inserted between edge of door and jamb with nut screwed to place. Fig. 4 shows a vertical section of bolt. Fig. 5 is a front end view 30 showing spurs at right angles to each other. Fig. 6 shows a cross and vertical section of nut.

The same letters refer to the same parts in 35 all the figures.

A in the drawings represents a cross-section of a door hung to door-jamb.

A' is a door-jamb.

B is my door-securer in place.

b' represents the thinnest side of the shank 40 of the bolt.

b² represents the thickest side of the shank of the bolt, which is for the purpose of filling different widths of the opening between edge of the door and the jamb.

b³ represents the thread on end of bolt. 45

b⁴ represents a hole in end of bolt and is for the purpose of putting same on a key-ring.

b⁵ represents the ends of the parallel sides of the shank, made wedge shape.

b⁶ represents the spurs on end of bolt. 50

C represents a transvertical section of nut.

C' represents a cross-section of nut.

The object of my invention is to furnish the traveling public and others with a door-securer which can be carried on an ordinary key-ring 55 and is applicable to any door. By the use of my bolt no one need fear burglars coming through the door unless they break the door in.

To operate or use my door-securer, first examine the space between edge of door and 60 jamb. If it is a wide crevice, insert bolt with long spur and thick shank, and if the crevice is small present the thinner side between the jamb and door. To insert the door-securer, open door ajar, screw nut back to end of 65 thread, insert the bolt so that the thread near the flat part of the shank is inside of the edge of jamb, insert with the spur toward the jamb, then shut the door and screw the nut up to the edge of the jamb and the door, and the 70 same is locked and cannot be opened from the outside.

Having thus described my invention, I claim as new and desire to secure by Letters Patent—

A door-securer consisting of the bolt or rod B, having the narrow and the wide parallel sides b' and b², the thread b³, the hole b⁴, and the beveled ends b⁵, with the ending spurs b⁶ b⁶, in combination with the exterior beveled 80 nut, substantially as shown and described.

JEREMIAH H. MATTHEWS.
